UNITED STATES PATENT OFFICE.

EDWARD M. COOK, OF OBERLIN, OHIO.

DISPLAY-CABINET FOR MERCHANDISE.

1,282,048.

Specification of Letters Patent. Patented Oct. 22, 1918.

Application filed June 20, 1917. Serial No. 175,775.

To all whom it may concern:

Be it known that I, EDWARD M. COOK, citizen of the United States, residing at Oberlin, in the county of Lorain and State 5 of Ohio, have invented certain new and useful Improvements in Display-Cabinets for Merchandise, of which the following is a specification.

This invention pertains to a display cabinet for retail merchandise, and in this instance particularly for caps and the like, and the object of the invention is to provide a cabinet with a number of subdivisions extending the full depth thereof from top 10 to bottom, six in this instance, and each subdivision having a number of compartments of such depth as to accommodate a single cap in each and preferably open at the front for advantageous display and examination of the goods, all substantially as shown and described and particularly pointed out in the claims.

In the accompanying drawings, Figure 1 is a side elevation of one form of cabinet 15 embodying my invention, and Fig. 2 is a vertical sectional elevation thereof. Fig. 3 is a sectional plan on a line traversing the hood above the lamps, and Fig. 4 is a plan view of the cabinet looking down on the hood. Fig. 5 is a cross section on line 5—5, Fig. 1.

The structure as thus shown comprises a cabinet body 2 rotatably supported upon a shaft 3 fixed in a base 4 and a specially 20 formed hood or section 5 on its top. The said body is circular and provided with six equal subdivisions extending the full length thereof and spaced apart by radially disposed walls 6, thus forming sub-divisions 25 of substantially V-shape in cross section, as seen in Fig. 5, and which flare outwardly. The said subdivisions are divided into a series of equal compartments by horizontal shelves 8 spaced apart a distance suitable to 30 accommodate a single cap or other article the cabinet is designed to display, and in this instance all caps of a given size are shown in one subdivision or column and those of another size or style in another 35 column, and so on. This obviously contributes to convenience the display and selection of sizes since all of one size are together, and facilitates choice and sale because all the caps or articles of that size 40 or style are together and easy to select by the person who makes the choice. Then 45

again the goods are protected from inter-mixture of numbers and shop wear, which is material to the merchant.

Further important details of construction 50 comprise the hood or top section 5 of the cabinet, and which has to do more especially with the illumination of the cabinet and in which means are required to afford continuous lighting while the cabinet is being 55 rotated. To these ends the said hood is of such size or width as to extend outward all around beyond the side of the cabinet at least far enough to mount electric lamps 60 10 therein in such position as to shed their 70 light down upon the front of the respective subdivisions, and reflectors 12 are provided for said lamps to assist in the illumination. A pair of lamps is shown for each of the six 75 subdivisions and electrical connection therewith is made by wires 15 through the shaft 3 from beneath and two commutator or contact rings 18 and 20, respectively, mounted upon said shaft over an insulating sleeve 21 thereon and which rings are electrically connected with the respective wires 15 in shaft 3 through said sleeve. This, of course, means that the said rings 18 and 20 are stationary with said shaft.

Two relatively larger conducting rings 22 85 and 23 are fixed in the hood on the top 24 of the cabinet on the same planes as the rings 18 and 20 and adapted to rotate therewith, and are suitably insulated and provided with suitable electrical connections 90 with the respective lamps 10. Contact brushes or members 25 and 26 respectively are slidably mounted in sockets in the rings 22 and 23 having springs 29 to press the said bolts or contact members in sustained 95 bearing against the smaller rings 18 and 20 to maintain a closed circuit. Then with a suitable switch in the system, not shown here, the salesman can manipulate the lights at his pleasure and maintain the light along 100 with free rotary control of the cabinet.

A lamp 27 is also shown on the top of shaft 3, and supports 28 are shown on the top of the hood for further display of the goods thereon.

What I claim is:

A display cabinet for merchandise comprising a body and a suitable base and a tubular shaft fixed in said base and having said body rotatable thereon, the said body 110 being provided with a plurality of radially disposed vertical walls and forming sub-

divisions from bottom to top, a hood mounted upon said body and having said shaft extending through the same and projecting laterally all around beyond the said body and provided with pockets for electric lamps adapted to shed their light downward about the said body, lamps in said pockets,

contact rings for the electric current in said hood, and wire connections therewith through said shaft.

Signed at Oberlin, in the county of Lorain and State of Ohio, this 2nd day of June, 1917.

EDWARD M. COOK.
